B. F. GOODRICH COMPANY, OF NEW YORK, N. Y., A CORPORATION OF NEW YORK.

GAS-MASK.

1,315,515.

Specification of Letters Patent.

Patented Sept. 9, 1919.

Application filed March 18, 1918. Serial No. 223,117.

To all whom it may concern:

Be it known that we, CHARLES W. KOHLER and FREDERICK H. MARTIN, citizens of the United States, residing at Akron, in the county of Summit and State of Ohio, have invented a certain new and useful Gas-Mask, of which the following is a specification.

This invention relates to gas masks of the type used in warfare, and its object is to furnish a light and flexible face-covering which shall be both waterproof and gas-proof.

The accompanying drawing is a side elevation, partly broken away, illustrating the construction of our improved mask.

The waterproofing alone is a comparatively simple matter and may be accomplished in known ways by using thin sheets of vulcanized rubber or fabric coated with rubber or with oils or waxes or combinations of these materials. Proofing against the passage of the extremely penetrating and poisonous gases used in modern warfare, such as phosgen, xylyl bromid, chlor picrin and others is much more difficult and has never been adequately accomplished prior to our invention, so far as we are aware. Thin rubber sheets or coatings are permeable by these gases. A fairly thick sheet of rubber will resist for a time but is open to the objection that it becomes saturated with the gas and afterward requires several hours exposure in a gas-free atmosphere in order to clear itself. Its thickness also diminishes its flexibility.

A coating composed of glue, glycerin and water acts very effectively as a gas-proofing means so long as it is kept pliable and non-porous, but is subject to the disadvantage of being soluble in water unless hardened or set in some way, as by means of formaldehyde. It has been proposed to use such a set or insoluble coating on a rubber or fabric foundation, but our experience has been that the coating, while sufficiently pliable when fresh, soon dries out and then cracks, chips or peels off so as to become of little use for its intended purpose. We are not aware of any single material or composition, usable in sheet form or as a coating, which is both waterproof and adequately gas-proof under conditions of warfare and at the same time permanently flexible.

We have found, however, that the desired

results may be obtained by providing a water-proof sheet, film or coating and a water-soluble, gas-proof sheet, film or coating on separate surfaces or separate plies of a plural-ply fabric or face-covering. Specifically, we employ a plurality of thicknesses of flexible material composed of or coated with rubber or other suitable waterproof substance on the two exposed surfaces, and having one or more interior sheets, coating, webs or films of a soluble gas-proof material such as the glue, glycerin and water mixture above mentioned, these thicknesses being preferably unconnected or free from each other except at the margins of the mask and at the edges where the eye-pieces and breathing attachments are connected, so as to secure the maximum degree of flexibility and other advantages. It is desirable to waterproof both the outer surface of the mask to exclude rain and snow, and its inner surface to prevent absorption of saliva and breath moisture.

Referring to the drawing, 1 is a gas mask having a flexible face-covering 2 provided with the usual eye-pieces 3, breathing fixture 4 and head-straps 5. As here shown, the body of the face-covering is composed of three plies or thicknesses of material, 6, 7, and 8, which are separate and free from each other except at the margins and around the eye-pieces and breathing fixture. This semi-freedom of the plies provides greater flexibility than if they were cemented together. It enables the mask to be crumpled or folded with no liability of cracking, permits the eye-pieces to be wiped free of moisture on the inside by doubling the covering in back of the windows without removing the mask, and diminishes the liability to total puncture of the covering by sticks or similar objects, since one or two of the plies can be perforated, and the other one or ones may yield without a complete penetration.

The outermost and innermost plies 6, 8 are preferably of thin woven fabric waterproofed in any suitable manner, as by spreading the fabric on one or both surfaces with several coats of rubber solution, then drying and vulcanizing. The middle plies 7 is preferably also made of woven fabric, very light in texture, and is coated with a soluble gas-proof material. For example, 100 parts by weight of animal glue is soaked for 24 hours in 100 parts of cold water and

then heated to about 90° C. until dissolved, after which 125 parts of glycerin is added and the mixture thoroughly stirred. A small quantity of bichlorid of mercury or 5 other preservative may be added to prevent putrefaction. The liquid is then applied to the cloth in successive coats by any suitable spreading method until the desired thickness is obtained, and when dry, the coated fabric 10 is ready for use. For the glue, other forms of gelatin, or casein, may be substituted and various other modifications made without departing from our invention.

We wish it understood that we may employ any equivalent for the particular gas-proofing and waterproofing elements here described, since our invention lies broadly in the idea of mechanically combining one or more waterproofing and one or more gas-proofing surfaces, webs, films, plies or coating substantially in the manner and for the purpose described, or for any analogous purpose, as well as in the nature of the gas-proofing means employed.

25 We claim:

1. A gas-mask comprising a face covering provided with suitable eye-pieces and a breathing connection, said covering including a waterproof ply or thickness and a 30 soluble gas-proof ply or thickness consisting of a substantially permanently flexible composition of glue and glycerin.

2. A flexible structure suitable for the face-covering of a gas mask, said structure 35 comprising adjacent plies of material, portions of which are disconnected and provided with two external waterproof surfaces and an internal gas-proof surface, other portions of said plies being connected to each other.

40 3. A flexible structure suitable for the face-covering of a gas-mask, said structure comprising adjacent plies of material having external waterproof surfaces and an interposed surface of soluble glue-glycerin 45 mixture, portions of said plies being disconnected from each other and other portions connected.

4. A gas-mask comprising a flexible face-covering having eye-pieces and a breathing fixture, said covering being formed of a 50 plurality of plies of material with their edges brought together at the margins and around said eye-pieces and breathing fixture, and their intermediate portions disconnected, the covering being waterproofed on 55 the outermost and innermost surfaces of the mask, and having, between the waterproofed surfaces, a soluble gas-proof surface of the nature of glue-glycerin mixture.

5. A flexible structure suitable for the 60 face-covering of a gas-mask, said structure comprising two waterproof plies of material, and an interposed third ply consisting of a sheet of cloth coated with gas-proof material.

6. A flexible structure suitable for the face-covering of a gas-mask, said structure comprising two waterproof plies of material, and an interposed third ply consisting of a sheet of cloth coated with soluble 70 glue-glycerin mixture, parts of said three plies being connected to each other and other parts free.

7. A gas-mask comprising visual and breathing devices and a flexible face-covering connected therewith, said covering comprising two waterproof plies of material, and an interposed third ply provided with a soluble gas-proof surface and mainly free from said waterproof plies.

8. A gas-mask comprising visual and breathing devices and a flexible face covering connected therewith, said covering comprising two plies of rubberized fabric, and an interposed third ply of fabric coated 85 with soluble glue-glycerin mixture and free from said rubberized plies on the portions thereof around the visual and breathing devices and within the margins of the face covering.

In testimony whereof we have hereunto set our hands this 15th day of March 1918.

CHARLES W. KOHLER.
FREDERICK H. MARTIN.
